A. SPARROW

BRAKE BEAM FULCRUM

Filed Oct. 27, 1921

Witness:

P. Burkhardt.

Inventor:

Arthur Sparrow,

By Wilkinson, Hawley, Bryson & Shright
Attys.

UNITED STATES PATENT OFFICE.

ARTHUR SPARROW, OF CHICAGO, ILLINOIS, ASSIGNOR TO AMERICAN STEEL FOUNDRIES, OF CHICAGO, ILLINOIS, A CORPORATION OF NEW JERSEY.

BRAKE-BEAM FULCRUM.

Application filed October 27, 1921. Serial No. 510,894.

To all whom it may concern:

Be it known that I, ARTHUR SPARROW, a citizen of the United States, residing at Chicago, in the county of Cook and State of Illinois, have invented certain new and useful Improvements in Brake-Beam Fulcrums, of which the following is a specification.

This invention relates to brake beams and more particularly to reversible fulcrums forming a part thereof.

One object of the invention is to provide a reversible fulcrum for the truss type of brake beam, which fulcrum may be reversed between right and left-hand positions in a manner to meet service requirements and at the same time provides a connection to the compression member of the brake beam without any longitudinal lost motion.

This and other objects are accomplished by means of the arrangement disclosed on the accompanying sheet of drawings, in which—

Figure 1 is a fragmentary side elevation of a brake beam embodying my invention, the tension and compression members being shown in section;

Figure 2 is a fragmentary top plan view of the same arrangement; and

Figure 3 is a fragmentary rear elevation of the same brake beam.

The various novel features of the invention will be apparent from the following description and drawings and will be particularly pointed out in the appended claims.

Referring to the figures of the drawings, it will be noted that I have disclosed my invention in connection with a truss type of brake beam including a compression member 10, a tension member 11 and a fulcrum post 12 extending therebetween.

It will be understood that a brake lever, not shown, may be pivotally connected to the fulcrum post 12 by means of a pin, not shown, extending through openings 13 in the side walls of the fulcrum post 12 the latter being provided with a flange 14 which engages the front surfaces of the flanges 15 of the compression member 10, thereby forming a frictional engagement between said flanges 14 and 15 for frictionally holding the reversible fulcrum post 12 in adjusted position. Extending outwardly toward the rear of the fulcrum post 12 from the flange 14 is a portion 16 having angular faces 17 for engaging the upper and lower flanges 15

of the compression member 10 for limiting reversible movements of the fulcrum post 12. Aside from the engagement of the faces 17 with respect to the compression member 10, no part of the portion 16 engages the compression member. Extending rearwardly from the portion 16 and formed integrally therewith is a conical projection 18 which extends through an aperture 19 in the web 20 of the compression member 10. The projection 18 is provided with a slot or opening 21 through which a wedge 22 is driven. The inclined surface 23 of the wedge engages the rear inclined wall 24 of the opening 21 and the front straight surface 25 of the wall engages the rear surface 28 of the web 20 of the compression member 10. Accordingly, when the wedge 22 is driven in place the flange 14 of the fulcrum post is drawn tightly against the edges of the flanges 15 of the compression member and the front surface 25 of the wedge 23 pressed tightly against the rear surface of the web 20 of the compression member 10, thereby eliminating all lost motion in the truss connection between the tension and compression members and at the same time the reversible fulcrum post 12 is frictionally held in its different adjusted positions.

The front end of the fulcrum post is provided with a seat 26 formed between projections 27 so shaped and spaced as to permit reversible movements of the fulcrum post 12.

It is my intention to cover all modifications of the invention falling within the spirit and scope of the following claims.

I claim:

1. In a brake beam, the combination of a compression member, a fulcrum post having an apertured portion extending beyond the compression member, and a wedge passing through the aperture in said fulcrum post at the rear of said compression member for holding said fulcrum post in position with respect to said compression member.

2. In a brake beam, the combination of a compression member, a fulcrum post having a portion extending beyond said compression member, and a wedge engaging the rear surface of said compression member and said portion of said fulcrum post for securing the latter in position.

3. In a brake beam, the combination of a tension member, a compression member, a

fulcrum post extending therebetween and having a portion extending beyond one of said members, and means cooperating with said extending portion and the rear surface of one of said members for holding the fulcrum post in position.

4. In a brake beam, the combination of a compression member, a fulcrum post having a flange adapted to engage said compression member, said fulcrum post also having a portion extending beyond said compression member, and means cooperating with said projecting portion of the fulcrum post and compression member for frictionally holding said flange and said compression member in frictional engagement for frictionally holding said fulcrum post in position.

5. In a brake beam, the combination of a compression member, a fulcrum post having a flange adapted to engage the compression member and also having a projection extending beyond said compression member, and a wedge cooperating with said extending portion and said compression member for holding said flange in engagement with said compression member for holding said fulcrum post in position.

6. In a brake beam the combination of a compression member, a fulcrum post having a portion adapted to engage said compression member and having an extension projecting through and beyond said compression member, and a wedge extending through said extension and coop-

erating with said compression member for forcing said portion of said fulcrum post into engagement with said compression member for holding the fulcrum post in position.

7. In a brake beam, the combination of a compression member of channel section, a reversible fulcrum post having a flange adapted to engage the outer end of the flanges of the compression member, said fulcrum post having a portion located within the flanges of the compression member for cooperating therewith to limit the reversible movements of said fulcrum post, said fulcrum post also having a projection extending through an opening in the web of said compression member, and a wedge passing through an opening in said projecting portion of the fulcrum post for forcing said fulcrum post flange into engagement with the compression member flanges for frictionally holding the fulcrum post in adjusted position.

8. In a brake beam, the combination of a compression member, a fulcrum post having a portion extending beyond said compression member, a wedge engaging the rear surface of said compression member and said portion of said fulcrum post for securing the latter in position, and means for limiting the reversible movements of said fulcrum post.

Signed at Chicago, Illinois, this 18th day of October, 1921.

ARTHUR SPARROW.
